METHOD OF BLENDING LIGHT HYDROCARBONS

Filed Jan. 16, 1920

UNITED STATES PATENT OFFICE.

HENRY COONEY, OF SUGAR GROVE, OHIO.

METHOD OF BLENDING LIGHT HYDROCARBONS.

Application filed January 16, 1920. Serial No. 351,827.

To all whom it may concern:

Be it known that I, HENRY COONEY, a citizen of the United States, residing at Sugar Grove, in the county of Fairfield and State of Ohio, have invented new and useful Improvements in Methods of Blending Light Hydrocarbons, of which the following is a specification.

This invention relates to the production of gasoline, and has for its object the method of blending and refrigeration, whereby the gasoline resulting from compression may be blended with the gasoline produced by distillation, and the blended gasoline so produced with its attendant vapors, may be refrigerated by expanding the residual gas or the gasoline produced by the high compressor, or both, thru a suitable heat exchanger.

20 In most of the absorption method gasoline manufacturing plants, the practice is to conduct the gasoline produced by the high and low stage compressors direct to storage tanks in some cases, or, more commonly, the gasoline is conducted to a weathering tank to free it of its volatile fractions, or to a naphtha blending tank.

It is the purpose of the present invention to conduct the gasoline accumulating in the receiving tank of the high pressure compressor, thru a trap into the receiving tank of the low pressure compressor, and the gasoline accumulating in the receiving tank of the low pressure compressor, delivered direct or thru a weathering tank to the main condenser, preferably to a point in this condenser at least twenty feet from its outlet.

The pressure carried on the low compressor varies, but ranges around 30 pounds per square inch. Since the gasoline accumulating in the receiving tank of this compressor is of a high Beaumé gravity, when it is expanded down to the pressure of the condenser (usually about eight inches water pressure) it has a marked cooling effect upon the hydrocarbon vapors, condensing fractions that otherwise would not liquefy. When the gasoline is led first to a weathering tank, then to the main condenser, the refrigerating effect is not so marked, as when led direct from the low accumulator tank. This refrigerating effect may be further increased by connecting a heat interchanger (or any similar apparatus) to the outlet from the main condenser, and using the

residual gas or the gasoline produced in the receiving tank of the high compressor as the refrigerants. By this means a temperature of 40 degrees Fahrenheit can be readily maintained on outlet from condenser in 60 degrees Fahrenheit weather. This heat interchanger offers the further advantage, when of ample dimensions, of reducing the pressure super-imposed upon the condenser by the discharging of the gasoline from the low receiving tank or weathering tank into it. The use of this heat interchanger, though not necessary to the blending feature of this invention, adds greatly to the efficiency of the method. When interchanger is not used, 70 the gasoline of compression is introduced directly into the outlet pipe of the main condenser.

In the drawing the figure shown illustrates the invention diagrammatically. 75

Referring more specifically to the drawings, the reference character 10 indicates the main or primary condenser, into which the gasoline produced by distillation is conducted thru a pipe 11. This method of distillation may be of any well known character, this purpose being to blend with the gasoline so produced, the gasoline resulting from compression, for the production of a gasoline of a high and a uniform grade. 80

For this purpose there is provided a heat interchanger 12, into which the condensed hydrocarbon vapors produced by distillation is blended with the gasoline produced by compression. The latter is introduced thru a pipe 13, which leads from trap 22 and which is in communication with the low pressure receiving tank, 18, and with weathering tank 20, line 13 being equipped with valves to permit use of either method. The 90 weathering tank prevents the main condenser outlet from freezing. Gasoline produced by high compressor 17, accumulating in receiving tank 16, may be delivered by trap 21, to low receiving tank 18, or to secure the maximum refrigerating effect, this gasoline may be conducted from trap 21, thru line 25 into compartment 14 of interchanger 12, leaving interchanger 12, thru line 26 to low receiving tank 18. As a further refrigerant residual gas from receiving tank 16 is expanded thru interchanger 12. This residual gas leaves receiving tank 16 thru pipe 33, regulator 23, and line 24, to compartment 15 of interchanger 12, thence 100 to compartment 14, leaving interchanger 12, thru line 26 to low receiving tank 18. As a further refrigerant residual gas from receiving tank 16 is expanded thru interchanger 12. This residual gas leaves receiving tank 16 thru pipe 33, regulator 23, and line 24, to compartment 15 of interchanger 12, thence 105 to compartment 14, leaving interchanger 12, thru line 26 to low receiving tank 18. As a further refrigerant residual gas from receiving tank 16 is expanded thru interchanger 12. This residual gas leaves receiving tank 16 thru pipe 33, regulator 23, and line 24, to compartment 15 of interchanger 12, thence 110

thru line 34 to field compressor (not shown) or consumption lines.

29 is a separating tank which receives the blended gasoline from the heat interchanger 5 12, through pipe 39^a. In this tank, very light fractions may evaporate, and any dissolved gases may be given off, these vapors and gases being led off, past the regulator 28, into the line 39. The light vapors given 10 off in the weathering tank 20 also enter the line 39, which line conducts these gases and vapors into the low pressure compressor 19.

The liquid gasoline blend, leaves tank 29 by pipe 40, in which is provided inspection 15 box 41, the blend being led to the storage tank 30.

Thus it will be readily seen by those skilled in the art that the hydrocarbon vapors produced by distillation are introduced 20 into the main condenser and the condensate delivered to the heat exchanger to be blended with the gasoline produced by compression. The blended gasoline passes through pipe 39^a to the separating tank 29 where 25 the liquid gasoline passes to the storage tank and the vapors evolved pass to the low pressure compressor to be returned to the system. The liquid from the low pressure compressor is conducted to the receiving 30 tank 18 while the gases and uncondensed vapors pass to the high compressor, the low pressure condensate passing through pipe 13 to the heat exchanger where the blending is done. The liquid from the high 35 compressor then passes (directly or indirectly) to the receiving tank 16 and the residual dry gas (which is very cold) passes by the pipe 24 to the heat exchanger and out to any suitable use through the pipe 40 34. The liquid from the tank 16 may pass through pipe 25 to the heat exchanger thence to the low compressor receiving tank by means of pipe 26.

45 By means of the above described apparatus, the gasoline produced by distillation may be blended with that produced by compression, the gasoline accumulating in the receiving tank of the low compressor being delivered direct or through the 50 weathering tank to the heat exchanger con-

denser, condensing fractions that otherwise would not liquefy. The low pressure gasoline may also first be conducted to the weathering tank and through the condenser and while the cooling effect will be considerable it is not so great as when led direct from the low pressure receiving tank.

55 By use of this apparatus, the gasoline produced by distillation may be blended with that produced by compression by expanding the residual gas to a separate compartment of the heat interchanger. This residual gas after leaving the interchanger may be returned to the compressors supplying gas to absorbers and may re-enter the 60 circuit again for treatment instead of being sent to the transportation line as is the common practice. This residual gas is rich 65 in gasoline contents.

70 The liquefied petroleum gas produced by high stage compressor may also be passed through the heat interchanger, that is, through the separate compartment and from the interchanger this liquefied petroleum gas may pass to the receiving tank 75 of the low stage compressor. This process also aids in refrigeration.

Having described the invention what is claimed is:—

80 A process of obtaining blended gasoline which comprises compressing natural gas having a gasoline content, first to a low stage of compression, cooling the same sufficiently to produce a low compression condensate, further compressing the remaining gases and vapors to a substantially higher stage of compression, cooling the 85 gases and vapors sufficiently to liquefy a second condensate passing at least a portion of such second condensate and the final gases after substantially lowering their pressure, in heat-conducting relation with a mixture comprising straight run gasoline and at least a portion of said first condensate and withdrawing any residual vapors from said 90 95 the last mentioned operation into the gas compression system.

In testimony whereof I affix my signature.

HENRY COONEY.
